UNITED STATES PATENT OFFICE.

GERARD JOHANNES EILERS, OF AMSTERDAM, NETHERLANDS.

HARD COURT FOR TENNIS AND THE LIKE.

Application filed February 9, 1928, Serial No. 253,188, and in the Netherlands January 6, 1927.

This invention relates to hard courts such as are used for playing tennis and the like, for the manufacture of which a drainage bottom layer is prepared of granulated material, 5 which is rolled to a firm bed in order to get a smooth and resilient floor. Certain disadvantages have hitherto been experienced when using such a paving, chiefly the following:—

First, these floors do often not afford a sufficient drainage for liquid so that they do not dry rapidly enough in order that play may be recommenced quickly after rain. Secondly, it often occurs that when endeavoring to form a porous top layer the uppermost layer is prepared with a material which is not sufficiently 10 repellent to footprints so that the required smooth surface is not retained. Finally, when trying to produce a solid and yet sufficiently draining top layer the disadvantage occurs 15 that the surface is too coarse, resulting in a too ready wear and tear of the shoes and of the balls and affording a risk of hurting the players when they fall.

The invention has for its object to remove 20 these inconveniences and consists of a court, which is formed by a bottom layer 1 of granulated, blast-furnace slags, coated with a layer 2 of finer and sifted slags of the same kind, as is shown in Figure 1 of the drawings in 25 cross-section.

According to the invention the paving can also be prepared by a bottom layer 1 of said slags above which is a layer 3 consisting of a

mixture of finer, sifted slags of the same kind and powdered bricks e. g. of red or green color or a similar binding material, as is shown in Figure 2 of the drawings in cross-section.

It will be found that a hard court produced according to the invention will present to the players a resilient, smooth paving with a 35 sufficiently solid and durable surface, affording an extraordinary good drainage for liquid. The materials used are porous and at the same time absorptive while they receive 40 binding qualities after some time.

I am aware that it has already been suggested to use not-granulated slags and bricks for the purpose of constructing tennis courts and the like, but the use of the particular material according to this invention, i. e. granulated slags, is a salient feature of my 45 invention.

What I claim is:—

A construction for a tennis court or the like comprising a bottom layer of coarse, 50 granulated blast furnace slags having a rough surface and many projecting parts, and a top layer interlocking with said bottom layer and including a mixture of finer, sifted, granulated blast furnace slags of the same general 55 character as the bottom layer and a binder of powdered brick dust.

In testimony whereof I affix my signature, at the city of Amsterdam, this 26th day of January, 1928.

GERARD JOHANNES EILERS.
